UNITED STATES PATENT OFFICE.

JOSEPH W. DOUGLAS, OF MIDDLETOWN, CONNECTICUT, ASSIGNOR TO
W. & B. DOUGLAS, OF SAME PLACE.

PUMP.

SPECIFICATION forming part of Letters Patent No. 244,384, dated July 19, 1881.

Application filed May 31, 1881. (Model.)

To all whom it may concern:

Be it known that I, JOSEPH W. DOUGLAS, of Middletown, in the county of Middlesex and State of Connecticut, have invented certain new and useful Improvements in Pumps; and I do hereby declare the following to be a full, clear, and exact description of the invention, such as will enable others skilled in the art to which it pertains to make and use it, reference being had to the accompanying drawings, which form part of this specification.

My invention relates to an improvement in pumps, and pertains more particularly to that class of pumps wherein the cylinder and spout are made of sheet-copper.

In copper pumps as heretofore constructed the spouts have been attached to the pump-cylinder by a wiped solder-joint located at the juncture of the spout and the outer surface of the cylinder. This method of attaching the spout to the cylinder has proved defective and objectionable for the following reasons: The joint between the spout and cylinder is necessarily weak, as the spout and cylinder at their point of juncture, being located practically at right angles to each other, afford but a comparatively small surface for the solder employed in securing the parts together, and hence it is often the case that the spout becomes loosened and detached from the cylinder, thereby entailing considerable trouble and expense in the necessary repairs. Again, a wiped solder-joint on the outside of the cylinder causes the finished pump to present a cheap, unfinished, and unworkmanlike appearance.

The object of my invention is to obviate the defective and objectionable features above referred to in this class of pumps, and to secure the spout to the cylinder in a thoroughly strong and durable manner, and at the same time conceal from view the solder or brazed joint between such parts.

With these ends in view my invention consists, essentially, in a copper pump-cylinder having a spout attached thereto by a solder or brazed joint located in a boss, nipple, or enlargement formed at the juncture of the spout and cylinder, whereby increased surface is insured between the adjacent portions of the spout and cylinder at their point of juncture, thereby af-

fording an extended joint-surface for firmly and securely attaching the parts together, and, further, enabling the solder to be concealed from view and giving a complete and finished appearance to the pump.

My invention further consists in certain features of construction and combinations of parts, as will hereinafter be described, and pointed out in the claims.

In the accompanying drawings, Figure 1 is a view, in side elevation, of a pump constructed in accordance with my invention. Fig. 2 is a vertical section, and Figs. 3 and 4 are vertical sections of modifications.

A represents the copper pump-cylinder, having a boss or nipple, B, projecting outwardly therefrom at a point where the spout is to be attached to the cylinder. The boss or enlargement B is formed by striking up the metal of the cylinder around the spout-opening C, thereby forming a converging or tunnel-shaped passage-way from the interior of the cylinder to the spout-opening C. The extreme outer end of the boss or nipple B is forced inwardly to conceal the raw edge of the metal and insure a smooth and finished edge, a.

D is the spout, one end of which is inserted in the spout-opening C, and adjusted so that its inner end shall be flush, or practically flush, with the inner surface of the pump-cylinder. It will thus be observed that by this construction a converging space, b, is formed between the inner end of the spout and the boss or nipple. Within this space b, and around the inner end of the spout, solder c is applied, and as the solder unites the inner surface of the boss or nipple on the cylinder to the outer surface of the inner end of the spout an extended joint is secured which is strong and durable. Not only is the joint thus produced much stronger than the ordinary wiped solder-joint, but, as will be observed, the solder is completely isolated from the outer and exposed surface of the pump, the smooth or finished edge or end a of the nipple or boss encircling the spout and constituting a finished copper joint on the outer side of the cylinder at its juncture with the spout.

Instead of forming a boss or nipple on the pump-cylinder, the joint may be formed as

shown in Fig. 3. In this form of construction the cylinder A has a spout-opening, C, formed therein in the usual manner. The inner end of the spout D is outwardly flared, as at E, and when the outwardly-flared end is placed over the spout-opening an annular gutter or chamber, e, is formed between the outer surface of the cylinder about the spout-opening and the inner surface of the flared portion E of the spout. Solder being allowed to flow into this chamber e, serves to firmly unite the spout to the cylinder by an extended solder-joint, which is also completely sealed from view.

In Fig. 4 the construction is the same as in Fig. 3, with the exception that a narrow flange or rim, f, is struck up around the spout-opening C in the cylinder, the diameter of said rim or flange being less than that of the outwardly-flared end of the spout. When the spout is applied an annular solder-chamber, g, is formed between the flared end of the spout and the rim f.

It is evident that many slight changes may be made in the form and relative arrangement of parts without departing from the spirit of my invention, and hence I would have it un-

derstood that I do not restrict myself to the exact form or arrangement of parts shown and described; but,

Having fully described my invention, what I claim as new, and desire to secure by Letters Patent, is—

1. A pump-cylinder having a spout secured thereto by a solder or brazed joint formed in a boss, nipple, or enlargement located at the juncture of the spout and cylinder, substantially as set forth.

2. A pump-cylinder having a nipple or boss formed about its spout-opening and a spout secured to the cylinder by a solder or brazed joint located between the outer surface of the inner end of the spout and inner surface of the nipple or boss on the cylinder, substantially as set forth.

In testimony that I claim the foregoing I have hereunto set my hand this 25th day of May, 1881.

JOSEPH W. DOUGLAS.
